UNITED STATES PATENT OFFICE.

WALTER S. GRAY, OF CHICAGO, ILLINOIS, ASSIGNOR TO GOODMAN MANUFACTURING COMPANY, OF CHICAGO, ILLINOIS, A CORPORATION OF ILLINOIS.

LOCOMOTIVE.

Application filed December 26, 1924. Serial No. 758,000.

This invention relates to improvements in locomotives of the type having a driving connection to both axles, from a single motor.

5 The principal object of the present invention is to provide, in a locomotive of relatively short wheel base, positive driving means from a motor to both axles, and further to provide in such a locomotive a maximum clearance between the wheels from the top of the rails to the lowest point on the drive gearing.

10 A further object is to provide in such a locomotive a flexible driving connection from the motor to a longitudinal shaft having geared connections with both axles and further, to provide means whereby both axles may be mounted for independent resilient movement.

15 20 The details of my invention may be best understood from the accompanying drawings, in which:

25 Figure 1 is a top plan view of a locomotive constructed in accordance with my invention, showing the position of driving shafts and gear housing upon the two axles relative to the wheels and framework of the locomotive;

30 Figure 2 is a side view of the locomotive shown in Figure 1 partly cross-sectioned to show details of the driving mechanism; and

35 Figure 3 is an enlarged transverse section taken on line 3—3 of Figure 2.

Referring now to the details of the drawings, I provide the locomotive 1 with side plates 7 and 8, axles 2 and 2^a, and supporting wheels 3, 3, and 4, 4. A motor 5 is supported by and suspended on brackets 6 and 6^a, which are fastened to the side plates 40 7 and 8, at one end of the locomotive, in any suitable manner.

45 Details of the driving mechanism are as follows:

The armature shaft 9 of the motor 5 is permanently joined to the driving shaft 10 by means of a universal joint 11. A similar universal joint 12 connects the shaft 10 to the shaft 13 which is journaled in the bearing 14. A spur gear 15 is mounted at the 50 opposite end of the shaft 13 and meshes with a spur gear 16 mounted on a centrally disposed longitudinal shaft 17 which is journaled in a tubular member 18. Bearings

23 and 24 for the shaft 17 are formed on each end respectively of the tubular member 18. A bevel pinion 19 is mounted at one end of the shaft 17 and meshes with a beveled gear 21 keyed to the axle 2. A similar pinion 20 is mounted at the opposite end of the shaft 17 and meshes with the beveled gear 22 keyed to the axle 2^a. It will be observed that the lower section of the bearing 14 and the upper portion of the tubular member 18 are integral while the lower section of the tubular member 18 and the upper section of the bearing 14 are detachably connected in any suitable manner, such as by means of bolts, around the axle 2 and the bevel gearing thereon so as to form a housing for the latter. The axle 2^a extends through a gear 70 housing, which is similar to the housing on the axle 2 and which comprises an upper part 25 and a lower part 26. The part 26 is clearly illustrated in Figure 3. The two parts 26 and 25 are bolted together and on 75 the inner side of the axle 2^a are shaped to encircle and to be rotatable about the bearing 24. On the outer side of the axle 2^a, each of the parts 25, 26, is formed with a semi-circular boss 25^a, 26^a, respectfully, 80 which together form a cylindrical extension to the housing. A bracket arm 27, formed integrally with the under portion of the bearing 14 and the upper portion of the tubular member 18, passes over the upper 85 housing part 25 and terminates in a bearing 27^a in which is received the cylindrical extension formed by the semi-circular bosses 25^a, 26^a. In this manner it will be seen the housing consisting of the parts 25, 26 has a 90 trunnion bearing connection with the housing 18 containing the shaft 17.

The arrangement is such as to afford a resilient movement of the parts, similar to a wrist movement, and insures a constant 95 contact of all four wheels with the rails while the locomotive is passing over irregular and uneven track, or when one axle is on a higher or lower level than the other.

While I have shown and described one embodiment of my invention, it will be understood that the arrangement and construction of the various parts may be altered without departing from the spirit and scope thereof. Furthermore, I do not wish to be 100 construed as limiting myself to the particu- 105

lar construction illustrated excepting as it may be specifically limited in the appended claim.

I claim as my invention:

- 5 In a locomotive having two axles, driving mechanism comprising a centrally disposed longitudinal driving shaft having geared connections at each end thereof with one of said axles, a motor mounted upon said locomotive, flexible means substantially parallel

to said driving shaft connecting said motor therewith at a point adjacent one of said axles, a centrally disposed longitudinal housing for said driving shaft, and means permitting rocking movement of either or both ¹⁵ of said axles.

Signed at Chicago in the county of Cook and State of Illinois, this 24th day of December, A. D. 1924.

WALTER S. GRAY.
